CLAIM

We claim, the ornamental design for an LED module, as shown and described.

DESCRIPTION

FIG. 1 is a front perspective view of a LED module showing an embodiment of our new design;

FIG. 2 is a rear perspective view of a LED module of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a front perspective view of a LED module showing another embodiment of our new design;

FIG. 10 is a rear perspective view of a LED module of FIG. 9;

FIG. 11 is a front view of FIG. 9;

FIG. 12 is a rear view of FIG. 9;

FIG. 13 is a left side view of FIG. 9;

FIG. 14 is a right side view of FIG. 9;

FIG. 15 is a top plan view of FIG. 9; and,

FIG. 16 is a bottom plan view of FIG. 9.
